(57) **CLAIM**

The ornamental design for a vehicle body, as shown and described.

DESCRIPTION

FIG. 1 is a front view of a vehicle body showing the new design;

FIG. 2 is a left front view thereof;

FIG. 3 is a left side view thereof, the right side being a mirror image thereof;

FIG. 4 is a top plan view thereof;

FIG. 5 is a left rear view thereof; and,

FIG. 6 is a rear view thereof.

In the drawing views, the tires and wheels form no part of the claimed invention.
